UNITED STATES PATENT OFFICE.

ROBERT S. CAMPBELL, OF STRAW PLAINS, TENNESSEE.

LUBRICATOR.

1,166,181.

Specification of Letters Patent. Patented Dec. 28, 1915.

Application filed June 21, 1913. Serial No. 775,095.

To all whom it may concern:

Be it known that I, ROBERT S. CAMPBELL, a citizen of the United States, residing at Straw Plains, in the county of Jefferson and State of Tennessee, have invented a new and useful Improvement in Lubricators, of which the following is a specification, reference being had to the accompanying drawing.

My improvement relates particularly to lubricators for rock drills operated by steam, compressed air, or similar elastic fluid; but the improvement is applicable also to lubricators for other machines.

The object of the improvement is to provide a lubricator which shall deliver oil in even quantities and be durable upon machines undergoing severe vibration or jarring. Rock drills and similar instruments operating by violent impact put severe strains upon lubricators, tending to destroy the lubricators and to make the feed uneven and unreliable, wastefully large quantities of oil being fed out or insufficient quantities being fed out and the machinery consequently injured for want of oil.

In the accompanying drawings, Figure 1 is an upright section of a lubricator embodying my improvement; Fig. 2 is a horizontal section on the line, 2—2, of Fig. 1; Fig. 3 is a horizontal section on the line, 3—3, of Fig. 1; Fig. 4 is a horizontal section on the line, 4—4, of Fig. 1, looking downward; Fig. 5 is a section on the same line, looking upward.

Referring to said drawings, A, is the body of the lubricator. At its lower end said body has a screw-threaded opening, 1, into which is threaded the column, B. Said column comprises a relatively large cylindrical lower portion, 2; an upper portion, 3, of less diameter, a cap, 4, spring, 5, annular plate, 6, and ball, 7. The lower portion, 2, of the column is exteriorly screw-threaded to fit into the opening, 1, in the body, A, and extend downward below the body to form a screw-threaded stem adapted to be threaded into the wall of the drill or other machine, and to receive a jam nut, 8, and bear against the lower end of the body.

The portion, 3, of the column, B, within the body, A, is of smaller diameter and its upper end is exteriorly screw-threaded. From its lower end to a point a little way above the bottom of the body, A, said column has a bore, 9, of suitable diameter only for the passage of steam or other elas-

tic fluid. Above said point said bore is large enough to receive a ball, 7, and a stem, 10, projecting downward from the cap, 4, and leaving space between said stem and the 60 wall of the column. The cap, 4, has a downwardly-directed interiorly-threaded flange, 11, fitting around the upper threaded portion, 3, of the column. In its top, said cap has a slot, 12, to receive a screw driver. In 65 the upper end of the body, A, is a threaded opening, 13, in which rests a plug, C. Said opening is to be of proper size to allow the insertion of a screw-driver or other tool for engaging the cap, 4, to turn the latter, and 70 for the insertion of lubricant.

The stem, 10, on the cap is long enough to nearly touch the ball, 7, when the latter rests on the seat formed around the enlarged upper portion of the bore, 9. A little way 75 above said seat, the wall of the column, B, has two apertures, 14, for the passage of oil from the body, A, into and downward through the column, B. Two similar apertures, 15, are formed in the cap above said 80 column. Said apertures are also for the passage of oil, as will be hereinafter described.

The lower face, 16, of the flange, 11, of the cap is made irregular, corrugated, or undulated. Beneath said cap, the portion, 3, 85 of the column is loosely surrounded by the annular washer or plate, 6, which has its upper face irregular, corrugated, or undulated. Said washer has an inner tooth, 17, which enters an upright groove, 18, on the 90 adjacent portion of the column to prevent said plate from turning on the column. Below said plate the expanding coiled spring, 5, surrounds the portion, 2, of the column and bears by its upper end against said plate 95 and by its lower end against the portion, 2, of the column, whereby said plate is constantly pressed upward against the annular face, 16, of the cap for the making of a frictional engagement between said plate and 100 said cap to restrain the rotation of the latter.

By practice I have repeatedly found that it is difficult to maintain this cap in position without the use of such a frictional resistance member. I have found that, without 105 such means for resisting the rotation of said cap, the cap will move downward more and more until it and the ball, 7, are bound tightly to the portion, 3, of the column. This, it will be seen, is due to the impact of 110 the drill tools against the rock, the action upon such cap being the same in nature as

the action upon an ordinary hammer or ax, when the handle is butted endwise against some relatively stationary object. Such action upon said cap is overcome by the resistance to rotation offered by said washer. Said washer is a yielding member resisting the rotation of said cap.

The lower portion, 2, of the column, B, is made a little larger than the diameter of the cap, C, in order that the column, with all its parts in place, may be removed through the lower portion of the body, A; or that the body, A, may be turned to run upward on the threads of the portion, 2, of the column, until it is free from the column, and then lifted entirely away, the opening, 1, of the body, A, being large enough to pass the column. This permits convenient separation of the parts to make adjustments and repairs. The ball, 7, tends to rest upon its seat and prevent the flow of oil from the body, A, downward through the lower portion of the column. The vibrations of the lubricator, which are transmitted to the latter during the operation of the drill, rock the ball and thereby cause it to leave its seat sufficiently to allow oil to flow downward through the bore of the column. The quantity of oil thus passing depends upon the degree of fluidity of the oil, the degree of vibration and the height of the cap stem, 10, above the ball. The thicker the oil, the less the vibration, and the closer the lower end of said stem stands to the ball when the latter is on its seat, the less will be the flow. For varying such flows, the cap is turned to raise or lower the stem, 10; and such adjustment is maintained by the action of the spring, 5, and the annular plate, 6, upon the cap, as already described.

When the drill is operated by steam, provision must be made for the accumulation of water of condensation in the lower portion of the body, A. This is done by plugging the apertures, 14, in the portion, 3, of the column adjacent the ball. The water coming from the condensation of steam passing upward through the column and through the apertures, 15, in the cap may accumulate in the portion of the body, A, below the level of said apertures. While said water thus rises, it lifts the oil more and more and allows it to flow into the column through said apertures, 15. When the water reaches said level, it must be removed. That may be done by drawing the drain plug, 19, in the lower portion of the body, A.

Thus the same mechanism constitutes an efficient lubricator for the use of either steam

or air, changing from air to steam requiring 60 merely plugging the apertures, 14, and changing from steam to air requiring merely the unplugging of said apertures, 14. This is an important feature; for some times on the same work some drills are operated with 65 air and others are at the same time operated with steam, and at times on the same work air is used a part of the time and steam is used another part of the time.

I claim as my invention:

1. In a lubricator, the combination of a hollow body having a screw-threaded opening in its bottom, a column extending into said body and having an enlarged lower cylindrical portion externally-threaded to 75 fit into said opening, such threading extending over a length exceeding the thickness of the wall around said screw-threaded opening plus the thickness of a jam-nut sufficient to leave a portion of said enlarged 80 portion for screw-threading into the wall of a machine after said enlarged portion has been threaded into the body, and a jam-nut, and said column having an axial bore extending from end to end and the upper 85 portion of said bore being larger than the lower portion, whereby a ball seat is formed, and said column comprising an adjustable cap and having an oil port, a ball located within said column between said seat and 90 said cap, and a jam-nut surrounding the enlarged portion of said column and bearing against the lower end of said hollow body, substantially as described.

2. In a lubricator, the combination of a 95 hollow body having a screw-threaded opening at its bottom, a column extending into said body and having an enlarged lower portion exteriorly-threaded to fit into said opening and extending below the latter, and said column having an axial bore extending from end to end and the upper portion of such bore being larger than the lower portion, whereby a ball seat is formed, and comprising an adjustable cap having a stem extending into said bore, and said column having an oil port, and a ball located within said column between said seat and said stem, substantially as described.

In testimony whereof I have signed my 110 name, in presence of two witnesses, this second day of June, in the year one thousand nine hundred and thirteen.

ROBERT S. CAMPBELL.
